UNITED STATES PATENT OFFICE

PERCY W. VALENTINE, OF NATICK, MASSACHUSETTS

STITCHDOWN SHOEMAKING MACHINE

Application filed July 13, 1929. Serial No. 377,947.

The present invention relates to machines for making stitch-down shoes with simultaneous performance of the steps of lasting the upper with an outturned edge flange, 5 stitching the flange of the upper to the flange of the innersole, and trimming off the edges of both flanges to approximately finished width. In its broader aspects the present invention is similar to that disclosed in my prior application for method and apparatus 10 for lasting and rough rounding stitch-down shoes, filed November 16, 1928, Serial No. 319,898. As compared with said prior application my present object and accomplishment 15 has been to provide a new and improved trimming knife by which the edges of the innersole and upper are trimmed and rounded more smoothly and effectively.

In its practical aspects as herein illustrated, the invention has been applied to a commercial sewing machine of a type which has long been on the market, wherefore in this illustration I have shown only so much of the previously existing machine as is necessary to explain the mode of attachment 25 of the new feature thereto and its cooperation with the previously existing means for pressing the flange of the upper against the innersole, forming the stitches of a seam, and 30 feeding the work.

Referring to the drawing,

Fig. 1 is a partial side elevation and vertical section of a machine embodying the present invention;

Fig. 2 is a vertical section on line 2—2 of Fig. 1;

Fig. 3 is a detail section on line 3—3 of Fig. 1;

Fig. 4 is a perspective view of the sole 40 rounding cutter;

Fig. 5 is a sectional view enlarged of the same taken on line 5—5 of Fig. 4;

Fig. 6 is a perspective view showing a fragment of a stitch-down shoe in process of being lasted and rough rounded in accordance with this invention.

Like reference characters designate the same parts wherever they occur in all the figures.

10 represents the base and 11 the over-

handing head of a commercial sewing machine of known type. 12 is an upright rising from the base on which is secured a work support 13. An awl 14 depends from the head and a needle 15 rises from the base, these parts cooperating with one another and with auxiliary stitch forming mechanism not shown, to pierce the outwardly extending flanges of the upper and innersole of a shoe 16, pass a thread through the holes so made, 55 feed the work forward, and form stitches uniting such flanges together. 17 is a presser depending from the head and operating by a reciprocating movement to draw the upper around the sides of a last step by step progressively in time with the feed of the work, and press the outturned flanges of the upper and sole together and against the work support adjacent to the point where the awl and needle pierce such flanges and place the sewing thread. The mechanism for operating these members in the manner and for the objects stated are not shown or described herein, as means suitable for these purposes are well known and understood by persons skilled 60 in the art.

Although the upright 12 is shown herein as mounted on cone pointed screws 18, this is a feature of the commercial sewing machine with which my new attachment has been associated to make the complete combination of the present invention, and has nothing to do with this invention. It is sufficient to say that during the operation of the machine this upright occupies the position shown in the drawing and is rigidly maintained therein.

The upright 12 is provided with a lateral sleeve 19 below the work support which provides a bearing for a rock shaft 20. On one end of the rock shaft is a rising arm 21 providing a carrier for a knife 22 which projects through slots in the work support 11 and presser 17, crossing the space between these members in which are received the outturning flanges of the shoe upper and innersole. On the other end of the rock shaft is an arm 23 engaged with a stud 24 on a driving arm 25 carried by a shaft 26 to which oscillative movement is given by means of well known 95 character, not necessary to be shown herein. 100

Arm 23 is pressed against the stud by a spring 27 which is coiled around the sleeve 19 and one end of which presses against a lug 28 on the side of the arm while the other reacts against a stud 29 on the sleeve. The face 30 of arm 23 which engages the stud 24 extends at an inclination to the path in which the stud travels with oscillation of arm 25, whereby downward movement of the latter arm causes arm 23 to swing in one direction, as shown by dotted lines in Fig. 2, while upward movement of arm 25 allows the spring 27 to return the arm 23 to the full line position. By this means the knife is oscillated in a path approximately parallel to the direction of work feeding, and in timed relationship to the steps of the feed, whereby at a convenient stage in the cycle of the feeding and stitch forming means, the knife advances with its cutting edge foremost, in the direction opposite to the feeding direction, and trims off the surplus stock at the edges of the innersole and upper.

Considered with respect to Fig. 2, the feeding direction is from right to left and the movement of the knife in cutting is from left to right. The cutting edge of the knife is its right hand edge, with respect to this figure. Thus the knife performs the operation of sole rounding simultaneously with the lasting and stitching operations. The effect in a partially completed shoe is shown in Fig. 6, where 16 represents the upper, 31 the innersole, 32 and 33 the contiguous flanges of the outturned upper and innersole, 34 the seam as far as it has been carried, and 35 the surplus stock cut off by the trimming knife. It is to be understood, however, that various other means for effecting the same character of relative movement between the knife and the work may be used within the scope of equivalents covered by the claims herein.

In order that the upper may be tucked well into the angle between the side of the last and the flange of the sole by means of a vertically reciprocating presser, the support 13 is arranged at an inclination and the adjacent face of the presser 17 is similarly inclined. As the knife is perpendicular to this inclination, and its operating rock shaft 20 is horizontal, it results that the knife travels in a slightly curved path, but its movement is so short that the deviation of its actual arc of travel from the straight line is so slight as to be practicably inappreciable and is less than the surplus width intentionally left in the flange to be removed by a final shaving step after the outsole has been applied. Indeed such curvature in the path of the knife as exists is of advantage in giving a smooth outline to the convex portions of the sole edge, which constitute the major proportion of the entire perimeter of the sole. However, it is within my

contemplation to arrange the knife exactly perpendicular to its rock shaft either with or without correspondingly altering the inclination of the work support or that of the rock shaft.

The effect of the oscillating knife is to trim the flange of the shoe with a smooth and a continuous edge, such that the successive steps of the cut merge into one another indistinguishably.

As showing the preferred means of mounting the knife holder on the rock shaft and detachably mounting the knife blade in the holder, attention is directed to Figs. 3, 4 and 5. The knife holder is provided with a hub portion 36 and with transverse threaded holes entering its bore from one side, in which are fitted set screws 37. That part of the rock shaft which enters the hub has a flat side 38 against which the two set screws abut near its opposite edges, whereby the arm is firmly secured without possibility of angular play. In the outer end of the knife holder is an undercut guideway 39 adapted to receive the knife blade and being intersected by a slot 40. The parts at the opposite side of the slot may be drawn together by a screw 41 so as to clamp the knife blade firmly in place.

The lasting phase of the operation carried out with the aid of this machine is performed in part by the operator who, while holding the shoe up to the action of the automatic means, also grasps the upper with his pincers and pulls it smooth over the last. In doing this he works on the upper near the automatic instruments of the machine and maintains a tension in the upper against which the presser acts when finally bringing it into the fully lasted position.

After completion of the operations herein described, the outersole is applied to the bottom of the lasted shoe and the shoe then finished in any suitable way; with this exception, that the usual step of rough rounding after applying the outersole is omitted. Owing to the rounding of the innersole performed with this machine, it is possible to provide outsoles cut from the side of leather to nearly finished dimensions, and having only such surplus stock as needed for final shaving to bring them exactly to a desired outline. That is, the approximation to finished dimensions thus given to the innersole enables an outsole cut to a substantially equal approximation to finished dimensions to be quickly and correctly applied to the lasted shoe, and eliminates the rough rounding operation which has been performed as a separate step after application of the outsole. This saves time and labor cost in the manufacture of the shoe and waste of good sole leather.

What I claim and desire to secure by Letters Patent is:

1. A machine for lasting, stitching and trimming stitch-down shoes, comprising pressing, piercing and stitch forming instrumentalities, a cutter mounted independently of said instrumentalities, and means for giving reciprocative movements to said cutter parallel to the direction of feed of the shoe in course of stitching. 70
2. A machine for use in lasting shoes comprising means for pressing together the flange of a shoe upper and the flange of an innersole adjacent to the side of a last within the upper, means for stitching a seam through said flanges and simultaneously feeding the shoe, and a rough rounding trimmer arranged across the space between said pressing means in which said flanges are received and being operable back and forth in a line substantially parallel to the direction of feeding. 75
3. An apparatus for use in lasting shoes comprising cooperating supporting and pressing means adapted to receive the flanges of an outturned shoe upper and innersole between them and to press said flanges together, means for stitching a seam through said flanges and feeding the work in a given direction, and a trimming knife extending across the space between said supporting and pressing means in which said flanges are received, having a cutting edge and being arranged with its width dimension substantially parallel to the direction of work feed, whereby said flanges are trimmed with a substantially smooth continuous edge in the course of feeding thereof. 80
4. An apparatus for use in lasting shoes comprising cooperating supporting and pressing means adapted to receive the flanges of an outturned shoe upper and innersole between them and to press said flanges together, means for stitching a seam through said flanges and feeding the work in a given direction, and a trimming knife extending across the space between said supporting and pressing means in which said flanges are received, having a cutting edge and being arranged with its width dimension substantially parallel to the direction of work feed, and means for reciprocating said knife substantially in the plane of its width dimension and in directions substantially parallel to the work feeding direction. 85
5. A machine for the purpose described comprising a work support, stitching, work feeding and pressing means, a knife crossing the supporting face of said work support, and means for moving said knife back and forth in directions approximately parallel to the direction of feed effected by said work feeding means. 90
6. An apparatus for use in lasting shoes comprising a work support adapted to support the sole, including the marginal por- 95
- tion thereof, of a shoe in process of being lasted, pressing means movable toward and away from said work support in position to press the upper of a shoe into the angle between the side of a last and the margin of the sole, stitch forming means arranged to form stitches uniting the marginal part of the sole to the outturned margin of the upper, and a cutter arranged to operate between the boundaries of said work support for trimming the innersole to rough round- 100
- ed dimensions. 105
7. A machine for lasting, stitching and trimming stitch-down shoes comprising pressing, piercing and stitch forming instrumentalities, a cutter mounted independently of said instrumentalities, and means for effecting relative linear movement between the cutter and shoe in the direction of progress of stitching, the cutter being located adjacent to the stitch forming instrumentalities whereby it trims the shoe outside of the line of stitches. 110
8. An apparatus for use in lasting shoes comprising cooperating supporting and pressing means adapted to receive the flanges of an outturned shoe upper and innersole between them and to press said flanges together, means for sewing a seam through said flanges, and a trimming knife extending across the space between the supporting and pressing means in which said flanges are received, and located near the seam sewing means, the knife and shoe being relatively moved, one with respect to the other, in the direction of progress of the seam whereby to trim the outstanding edges of said flanges. 115
- In testimony whereof I have affixed my signature. 120
